Specification for Design.

Patented Sept. 22, 1914.

Application filed July 29, 1913. Serial No. 781,885. Term of patent 14 years.

To all whom it may concern:

Be it known that I, WILLIAM SCHAAKE, a citizen of the United States, residing in the city of Pittsburgh and State of Pennsylvania, have invented a new, original, and ornamental Design for Insulators, of which the following is a specification.

My design is illustrated in the accompanying drawing, in which—

Figure 1 is a plan view and Fig. 2 and Fig. 3 are views in side elevation, taken at right angles to each other, of an insulator embodying my invention.

I claim—

The ornamental design for an insulator, as shown.

In testimony whereof, I have hereunto subscribed my name this 16th day of July, 1913.

WILLIAM SCHAAKE.
